MOTION CONVERTER

Fred A. Lane, Shelburn, Ind., assignor to Lane Motors, Inc., Terre Haute, Ind., a corporation of Indiana

Application April 8, 1946, Serial No. 660,493

6 Claims. (Cl. 74—57)

1

The object of the present invention is to provide a motion converter which shall be capable of efficiently converting rotation of one element into reciprocation of another, or vice versa. It is intended to provide a structure which shall accomplish these functions with minimum wear and maximum life, and which shall be extremely inexpensive to produce, simple to repair, and rugged in construction. Further objects of the invention will appear as the description proceeds.

To the accomplishment of the above and related objects, my invention may be embodied in the form illustrated in the accompanying drawings, attention being called to the fact, however, that the drawings are illustrative only, and that change may be made in the specific construction illustrated and described, so long as the scope of the appended claims is not violated.

Fig. 1 is a more or less diagrammatic view of my invention embodied in a pump;

Fig. 2 is a transverse section taken substantially on the line 2—2 of Fig. 1.

Fig. 3 is a sectional projection taken upon the line 3—3 of Fig. 1; and

Fig. 4 is a transverse section taken on the line 4—4 of Fig. 1.

In the illustrated embodiment of my invention, an elongated housing 10 is closed at one end by a removable head 11 and at the other end by a removable head 12 formed with a cylindrical aperture 13 in which is preferably mounted a lubricating bushing 14 forming a bearing for a rotary shaft 15.

Adjacent the head 11 the housing may be formed with a peripheral flow passage 16 opening through radial ports 17 and 18; and a similar passage 19 is formed adjacent the head 12, opening through ports 20 and 21. Said passages, of course, communicate with the cylindrical bore 22 which extends through said housing 10 from end to end thereof.

Rotatably mounted in that end of the bore 22 adjacent the head 12 is a cylindrical block 23 connected to rotate with the shaft 15 and, in the illustrated embodiment of my invention, integral with said shaft. Said block 23 is bored to provide a cylinder 24, opening through the inner end of said block 23, and formed upon an axis parallel with, but offset with respect to, the axis of rotation of said block 23. Said cylinder 24 is formed with a radial port 25 registering with the passage 19.

Formed upon another axis, parallel with, but offset with respect to, the axis of rotation of the

2

block 23 is a socket 26 whose function will appear hereinafter.

5 Rotatably received in the bore 22 adjacent the head 11 is a second cylindrical block 27. Said block is formed with a cylinder 28 which opens through the inner end of said block and whose axis is parallel to the axis of rotation of the block 27, but offset therefrom by an amount equal to the offset of the axis of the cylinder 24, so that the axes of cylinders 24 and 28 may be brought into alignment. Said cylinder 28 is formed with a radial port 29 registering with the passage 16. A socket 30 is formed in the block 27, opening through the inner end thereof, and formed upon an axis which will be aligned with the axis of the socket 26 when the axes of the cylinders 24 and 28 are in alignment.

10 A bar 31 is formed with a reduced end 32 which is received in the socket 26 of the block 23, the reduction of said end 32 providing a shoulder 33 bearing against the inner surface of the block 23. At its opposite end, the bar 31 is similarly reduced, the reduced portion 34 being received in the socket 30, and the shoulder 35 bearing against the inner 15 face of the block 27.

15 A cam member 36 is formed with an eccentric bore 37 through which extends the body portion of the bar 31, said cam member being slidably associated with said bar 31, and being mounted for rotation and reciprocation in the housing bore 22. A port 38 extends from end to end of said member 36 to permit fluid flow past said cam member as it reciprocates.

20 Projecting from one end face of the cam member 36 is a piston 39 which, in the illustrated embodiment of the invention, is shown to be integral with the member 36, and which carries a piston 40 reciprocably mounted in the cylinder 24. From the opposite end face of the member 36 projects a similar piston rod 41 carrying a piston 42 reciprocably received in the cylinder 28.

25 A cylindrical journal surface 43 is formed by cutting into the periphery of the cam block 36, the axis of said journal surface being inclined to the axis of rotation of the blocks 23 and 27. Journalled upon said surface 43 is a split ring 44 which is provided, at one point in its periphery, with a radial opening 49.

30 In an enlargement 45 of the housing 10 there is formed a cylindrical socket 46, upon an axis lying in a plane normal to the axis of rotation of the blocks 23 and 27, and midway between the ends of the housing bore 22. Oscillably received in said socket 46 is a rocker pin 47 formed with a transverse bore 48 with which is adapted to regis-

ter said opening 49 in the ring 44. A pin 50 has its opposite ends received in the opening 49 and the bore 48 to provide a restraining connection between said rocker 47 and the ring 44. By such connection, the ring 44 is restricted, in its movement, to oscillation about the axis of the socket 46. The open end of said socket is closed by a threaded plug 51.

It will be obvious that the engagement of the pistons 40 and 42 in the cylinders 24 and 28, and the engagement of the reduced ends 32 and 34 of the bar 31 in the sockets 26 and 30, and the engagement of said bar in the bore 31, will constitute the elements 23, 21, and 36 a rotationally rigid structure. Thus, although the block 23 may be considered a rotor and the block 27 may be considered another rotor, and although the element 36 is reciprocable relative to said blocks, the whole assembly of blocks 23 and 27 with their cylinders 24 and 28, pistons 40 and 42, and cam element 36, may be considered as a single rotor.

When the shaft 15 is rotated, in a clockwise direction, for instance, as viewed in Fig. 2, the engagement of the ring 44 upon the journal surface 43, and the connection of said ring to the rocker 47, will cause the cam element 36 to be moved toward the right, as viewed in Fig. 1. A quarter turn of the shaft 15 (and so, of all of the parts within the housing bore 22 except the ring 44 and pin 50) will swing the ring 44 into a vertical plane, said ring moving about the axis of the rocker 47. Note that initial movement of the rotor in a clockwise direction moves the port 25 out of communication with the port 21 and into communication with the port 20. Such movement of the ring 44 into a vertical position causes cam element 36 to be moved toward the right, whereby the piston 40 is drawn toward the open end of its cylinder 24, so that fluid, for instance in a reservoir connected to the port 20, will be drawn into the cylinder 24. Concurrently, the piston 42 will be driven more deeply into its cylinder 28, while the port 29 is in communication with the port 18, whereby fluid in the cylinder 28 will be expelled through said port 18.

Another 90° of rotation of the shaft 15 will shift the cam member 36 to the right hand limit of its stroke, in which the ring 44 will be inclined to the axis of the housing bore 22 to an extent equal and opposite to that illustrated.

During the stroke of the cam element 36 toward the right, the port 25 is in communication with the port 20, and closed from communication with the port 21 by the projections 52 and 53 formed on the housing 10 and extending into contact with the block 23 to obstruct the groove 19; and similar structure maintains the port 29 in communication with the port 18 and out of communication with the port 17. As rotation of the shaft 15 continues beyond the 180° thus far described, the port 25 moves past the projection 52 and therefore comes into communication with the port 21 and leaves communication with the port 20. Similarly, the port 29 leaves communication with the port 18 and enters communication with the port 17. Such further rotation causes the journal surface 43 to swing the ring 44 in a clockwise direction about the axis of the rocker 47, so that the pistons 40 and 42 will move toward the left to draw fluid through the port 17 into the cylinder 28 and to expel fluid from the cylinder 24 through the port 21.

Obviously, as the ring 44 swings about the axis of the rocker 47, the pin 50 must reciprocate relative to the rocker 47 or to the ring 44, or both.

It is my present belief that, if the ends of the housing 10 are suitably modified to provide for the admission to, and exhaust from, the cylinders 24 and 28, of combustible fuel and exhaust gases, the disclosed structure can be made to operate as an internal combustion engine to drive the shaft 15.

I claim as my invention:

1. A motion converter comprising a housing having a cylindrical bore, a rotor mounted in said housing bore, a pair of aligned, inwardly-opening cylinders formed in said rotor upon an axis eccentric with respect to the axis of said rotor, a piston for each of said cylinders, each piston being reciprocable in its cylinder, means in said housing and reciprocable relative to said rotor but rotatable only with said rotor, said means being formed to provide a journal surface on an axis inclined to the axis of rotation of said rotor surface, an element journaled on said journal surface, and means retaining said element against rotation with said rotor but permitting oscillation of said element about a fixed external axis.

2. A motion converter comprising a housing having a cylindrical bore, a rotor mounted in said housing bore, a cylinder formed in said rotor upon an axis parallel with, but offset with respect to, the axis of said rotor, and having one open end, a piston reciprocably received in said cylinder, means mounted in said housing bore for reciprocation relative to said rotor, but constrained to rotate with said rotor, said means being fixed to said piston and further being formed to provide a journal surface on an axis inclined to the axis of rotation of said rotor, an element journaled on said journal surface, and means swingable about a fixed axis outside said rotor and held against non-radial movement relative to said element.

3. A motion converter comprising a housing having a cylindrical bore, a rotor element mounted in said housing bore adjacent one end thereof, a second rotor element mounted in said housing bore adjacent the other end thereof, a cylinder eccentrically formed in each of said rotor elements, said cylinders being coaxial and opening toward each other, a member reciprocably and rotatably mounted in said housing bore between said rotor elements, a piston carried on said member, projecting from one end thereof, and reciprocably received in the cylinder of said first-named rotor element, a second piston carried on said member, projecting from the other end thereof, and reciprocably received in the cylinder of said second rotor element, a journal surface formed on said member on an axis inclined to the axis of rotation of said rotor elements, an element journaled on said journal surface, and means constraining movement of said last-named element to oscillation about a fixed axis outside said housing bore, said axis of oscillation being disposed in a plane normal to the axis of rotation of said rotor elements and midway between the ends of the strokes of said pistons.

4. A motion converter comprising a housing having a cylindrical bore, a rotor element mounted in said housing bore adjacent one end thereof, a second rotor element mounted in said housing bore adjacent the other end thereof, a cylinder eccentrically formed in each of said rotor elements, said cylinders opening toward each other, a member reciprocably and rotatably mounted in said housing bore between said rotor elements, a piston carried on said member, projecting from one end thereof, and reciprocably received in the

cylinder of said first-named rotor element, a second piston carried on said member, projecting from the other end thereof, and reciprocably received in the cylinder of said second rotor element, a journal surface formed on said member on an axis inclined to the axis of rotation of said rotor elements, an element journalled on said journal surface, and means constraining movement of said last-named element to oscillation about a fixed axis outside said housing bore, said axis of oscillation being disposed in a plane normal to the axis of rotation of said rotor elements and midway between the ends of the strokes of said pistons.

5. A motion converter comprising a housing having a cylindrical bore, a rotor element mounted in said housing bore adjacent one end thereof, a second rotor element mounted in said housing bore adjacent the other end thereof, a cylinder eccentrically formed in each of said rotor elements, said cylinders opening toward each other, a member reciprocably and rotatably mounted in said housing bore between said rotor elements, a piston carried on said member, projecting from one end thereof, and reciprocably received in the cylinder of said first-named rotor element, a second piston carried on said member, projecting from the other end thereof, and reciprocably received in the cylinder of said second rotor element, a journal surface formed on said member on an axis inclined to the axis of rotation of said rotor elements, a ring journalled on said journal surface, a pin operatively associated with said ring and projecting radially therefrom and held against non-radial movement relative thereto, and a rocker mounted in said housing outside said bore for oscillation about a fixed axis disposed in a plane normal to the axis of rotation of said rotor elements and midway between the ends of 40

the strokes of said pistons, the end of said pin remote from said ring being held in said rocker.

6. A motion converter comprising a housing having an elongated cylindrical bore, a cylindrical block rotatably mounted in said bore adjacent one end thereof, a cylinder formed in said block and having an open end facing the opposite end of said bore, a second cylindrical block rotatably mounted in said bore adjacent the opposite end thereof, a cylinder formed in said second block and having an open end facing said first-mentioned block, said cylinders having a common axis parallel with, but offset with respect to, the common axis of rotation of said blocks, said blocks further being formed with aligned sockets parallel with, but offset with respect to, both said axes, a bar formed at its opposite ends for reception in said sockets, respectively, to hold said blocks against movement toward each other, a member received in said housing bore between said blocks and slidably mounted on said bar, pistons carried by said member and reciprocably received in said cylinders, respectively, a journal surface formed on said member upon an axis inclined to the axis of rotation of said blocks, and a member journalled on said journal surface and constrained to oscillation about a fixed axis outside said housing bore.
